UNITED STATES PATENT OFFICE

168,273

PLAY SUIT

Florence Lorraine Gerber Mason, Columbus, Ga.

Application January 24, 1952, Serial No. 18,198

Term of patent 3½ years

(Cl. D3—17)

To all whom it may concern:

Be it known, that Florence Lorraine Gerber Mason, a citizen of the United States of America, residing at Columbus, in the county of Muscogee and State of Georgia, have invented a new, original, and ornamental Design for a Play Suit, of which the following is a specification, reference being had to the accompanying drawing forming part thereof.

In the drawings:

Fig. 1 is a front perspective view of a play suit showing my new design;

Fig. 2 is another front perspective view of the play suit shown in Fig. 1, and

Fig. 3 is a rear elevational view thereof.

What I claim as my invention is:

The ornamental design for a play suit, as shown.

FLORENCE LORRAINE GERBER MASON.
